197,530

LIGHTING FIXTURE

Joseph L. Jaffe, Jr., Shaker Heights, and Arthur E. Crisfield, Parma, Ohio, assignors to The Perfeclite Company, Cleveland, Ohio, a corporation of Ohio

Filed June 28, 1962, Ser. No. 70,717

Term of patent 14 years

(Cl. D48—4)

FIG. 1 is a front perspective view of a lighting fixture embodying our new design;

FIG. 2 is a side elevation; and,

FIG. 3 is a bottom view.

The top is substantially flat and plain and the rear is open and substantially plain.

We claim:

The ornamental design for lighting fixture, as shown and described.

References Cited in the file of this patent

UNITED STATES PATENTS

2,898,449 Urengdenhil ----- Aug. 4, 1959

OTHER REFERENCES

Mobile Home Dealer, Aug. 20, 1960, page 84, upper lefthand corner, wall lamp.